Primary Examiner — Sheryl Lane*Assistant Examiner* — Iesha N Price(74) *Attorney, Agent, or Firm* — James L. Young; Westman, Champlin & Koehler, PA(57) **CLAIM**

The ornamental design for a packaging fastener, as shown and described.

DESCRIPTION

FIG. 1 is a perspective view of a packaging fastener;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines in the drawings illustrate portions of the packaging fastener and form no part of the claimed design.
